UNITED STATES PATENT OFFICE

114,835

DESIGN FOR A BRACELET

George Dewey Sullivan, New York, N. Y., assignor to Trabert & Hoeffer, Inc., New York, N. Y.

Application December 31, 1937, Serial No. 74,020

Term of patent 3½ years

To all whom it may concern:

Be it known that I, George Dewey Sullivan, a citizen of the United States, residing at 407 Park Avenue, city of New York, in the county of New York and State of New York, have invented a new, original, and ornamental Design for Bracelets, of which the following is a specification, reference being had to the accompanying drawing, forming part thereof.

In the drawing:

The figure is a perspective view of a bracelet showing my new design.

I claim:

The ornamental design for a bracelet, substantially as shown.

G. DEWEY SULLIVAN.
